DESIGN FOR A COMBINED DESK CLOCK AND CALENDAR

James H. Horsley, Chicago, Ill., assignor to
Shanklin Manufacturing Company, Chicago,
Ill., a corporation of Illinois

Application May 23, 1940, Serial No. 92,533

Term of patent 7 years

To all whom it may concern:

Be it known that I, James H. Horsley, a citizen of the United States and resident of Chicago, in the county of Cook and State of Illinois, have invented a new, original, and ornamental Design for a Combined Desk Clock and Calendar, of which the following is a specification, reference being had to the accompanying drawing, forming a part thereof.

Fig. 1 is a perspective view of a combined desk

clock and calendar, showing my new design, the numerals and printed matter being merely representative.

Fig. 2 is a side elevational view of the same.

Fig. 3 is a rear elevational view of the same.

I claim:

The ornamental design for a combined desk clock and calendar, substantially as shown and described.

JAMES H. HORSLEY,
